BANDOLIER WITH POCKET

Claudie C. Burthey, 1013 Elmira Ave.,
Durham, N.C. 27707

Filed July 19, 1974, Ser. No. 489,908

Term of patent 14 years

Int. Cl. D3—02

U.S. Cl. D87—1 R

FIG. 1.

FIG. 2.

FIG. 3.

FIG. 5.

FIG. 4.

FIG. 6.

FIG. 7.

FIG. 1 is an exploded front perspective view of a bandolier with pocket showing my new design and in which the detachable strap is shown separated from the main body portion of the bandolier;

FIG. 2 is a perspective view similar to FIG. 1 but taken from the rear and below the bandolier;

FIG. 3 is a plan view to reduced scale;

FIG. 4 is a front elevational view to reduced scale;

FIG. 5 is a left side elevational view of FIG. 4;

FIG. 6 is a right side elevational view of FIG. 4; and

FIG. 7 is a bottom plan view of FIG. 4.

I claim:

The ornamental design for a bandolier with pocket, as shown.
